UNITED STATES PATENT OFFICE.

ALLEN PARKER WILSON, OF WALTHAM, MASSACHUSETTS, ASSIGNOR TO BOSTON PENCIL POINTER COMPANY, OF WALTHAM, MASSACHUSETTS, A CORPORATION OF MASSACHUSETTS.

METHOD OF MAKING CUTTERS FOR PENCIL-SHARPENERS.

1,383,045.

Specification of Letters Patent. Patented June 28, 1921.

Application filed April 21, 1919. Serial No. 291,521.

To all whom it may concern:

Be it known that I, ALLEN P. WILSON, a citizen of the United States, and resident of Waltham, in the county of Middlesex and State of Massachusetts, have invented a new and useful Improvement in Methods of Making Cutters for Pencil-Sharpener, of which the following is a specification.

This invention relates to improvements in the method of making cutters for pencil sharpeners, with the object in view of providing a hollow cutter which is developed from sheet metal.

Another object is to provide a cutter of this character in which a sheet metal blank is distorted to produce one or more pencil sharpening ribs and the blank then being curved and its side edges united to form a tube having the sharpening rib or ribs arranged spirally and exteriorly thereon.

A practical embodiment of my invention is represented in the accompanying drawings in which,—

Figure 1. represents a plan view of a piece of sheet metal from which the blank for my improved cutter is taken.

Fig. 2. represents an edge view of the same.

Fig. 3. represents a plan view of the blank distorted to produce the pencil sharpening ribs thereon.

Fig. 4. represents a section taken in the plane of the line IV—IV of Fig. 3.

Fig. 5. represents a side view of the cutter, the pencil sharpening ribs being shown arranged spirally and exteriorly thereon.

Fig. 6. represents an end view of the same.

Fig. 7. represents a central section of the same.

The cutter comprises a tube 1 shown cylindrical in the present instance, and it is produced as follows. A blank 2 of rhomboidal form is cut from a piece of sheet metal 3 and it is distorted by stamping, rolling, or otherwise to produce pencil sharpening ribs 4 which project outwardly from the surface of the blank. These sharpening ribs are formed parallel to the diagonal side edge 6 so that when the blank is curved into its tubular form the sharpening ribs will be arranged spirally and exteriorly thereon, with

the abutting side edges 6 meeting at a point between two sharpening ribs, as clearly shown in Fig. 5. These side edges 6 may be permanently united by any well known or approved means.

The curving of the blank into its tubular form may be accomplished by any suitable device of well known or approved type.

It is to be understood that after the above operations are completed the tube may be hardened by any well known or approved process and if so desired the exterior spiral sharpening ribs may be suitably sharpened.

What I claim is:

1. The method of producing sheet metal cutters for pencil sharpeners comprising distorting a sheet metal blank to produce one or more pencil sharpening ribs curving the blank into a tube having the rib or ribs arranged exteriorly thereon, and uniting the meeting edges of the blank.

2. The method of producing sheet metal cutters for pencil sharpeners comprising distorting a sheet metal blank to produce one or more pencil sharpening ribs curving the blank into a tube having the rib or ribs arranged exteriorly thereon, uniting the meeting edges of the blank and sharpening said ribs.

3. The method of producing sheet metal cutters for pencil sharpeners comprising distorting a sheet metal blank of rhomboidal form to produce one or more diagonal pencil sharpening ribs, curving the blank into a tube having the rib or ribs arranged spirally and exteriorly thereon and uniting the meeting edges of the blank.

4. The method of producing sheet metal cutters for pencil sharpeners comprising distorting a sheet metal blank of rhomboidal form to produce one or more diagonal pencil sharpening ribs, curving the blank into a tube having the rib or ribs arranged spirally and exteriorly thereon, uniting the meeting edges of the blank and sharpening said ribs.

In testimony that I claim the foregoing as my invention I have signed my name this 14th day of February, 1919.

ALLEN PARKER WILSON.
